[57] CLAIM

The ornamental design for a cutting anvil, as shown and described.

DESCRIPTION

FIG. 1 is an oblique view of a cutting anvil showing my new design;

FIG. 2 is a front elevational view thereof;

FIG. 3 is a bottom plan view thereof;

FIG. 4 is a rear elevational view thereof; and,

FIG. 5 is an oblique view of a second embodiment of the cutting anvil, the embodiment of FIG. 5 being a mirror image of the embodiment shown in FIGS. 1-4.

The broken line showing in FIGS. 1, 2 and 5 is for illustrative purposes only and forms no part of the claimed design.
